UNITED STATES PATENT OFFICE.

HAROLD T. BAKER, OF DAYTON, OHIO, ASSIGNOR TO THE MANAGEMENT, ENGINEERING AND DEVELOPMENT COMPANY, OF DAYTON, OHIO, A CORPORATION OF OHIO.

HOOD-INSULATING MEANS FOR DRYING-MACHINES.

1,397,309.

Specification of Letters Patent. Patented Nov. 15, 1921.

Application filed April 16, 1921. Serial No. 461,981.

To all whom it may concern:

Be it known that I, HAROLD T. BAKER, a citizen of the United States, residing in the city of Dayton, in the county of Montgomery and State of Ohio, have invented certain new and useful Improvements in Hood-Insulating Means for Drying-Machines, of which the following is a specification.

- 10 The principal object of the invention is to provide insulating means for the under surface of the hoods of drying machines, and more particularly, but not necessarily, paper and pulp drying machines. While 15 these insulating means preferably comprise a combination of gypsum and asbestos to prevent the condensation of saturated air on the undersurface of the hood, any other materials which will effect the same result 20 are included within the scope of the invention. These insulating means are also designed to make the hood fireproof, and are adapted to be readily installed in the hood frame for a firm support thereby.
- 25 Other important and incidental objects will be set forth in the following specification, and particularly pointed out in the subjoined claims.

In the accompanying drawings, Figure 1 30 is a perspective view of a paper drying machine, whose hood is partly broken away to reveal the insulating means applied to the undersurface thereof. Fig. 2 is a side elevational view of a section of the hood frame, 35 showing how my insulating means are supported thereby. Fig. 3 is a side elevational view of a section of the hood frame, showing how the latter may be supported from the roof of an inclosing building and also 40 the uptake which conducts the vapor-laden air from the interior of the hood to the outside air. And Fig. 4 is a cross section of the hood frame, taken on the line *a—a* of Fig. 2, showing the corrugated asbestos and gypsum insulation therein.

Throughout the specification and drawings, similar reference characters denote corresponding parts.

Referring to the accompanying drawings 50 for a detailed description of the preferred form of embodiment of my invention, the numeral 1 designates the inclosing frame of a series of paper dryers 2 disposed in a manner well known in the art. Mounted upon

each side of the frame 1, is a series of upright supporting members 3, connected by truss rods 3^a, for a hood now to be described.

Bolted to the tops of the upright members 3 are longitudinal I beam members 4 and end channel members 4^a, those on one side 60 inclining upwardly for connection to those on the opposite side by means of a connection block 4^b, to form with the truss rods 3^a a triangular truss frame for the hood. Disposed between the I beam members 4 in rows 65 that are a substantial distance apart, are transverse channel members 5 which are connected to the I beam members 4 by clip angles 6. (See Figs. 2 and 4.)

In Fig. 3 I have shown a hood frame 70 which is supported from the roof of the building (not shown) by rods 7 that are connected at their lower ends to the I beam members 4. The insulating means, now to be described, are adapted to be installed in 75 hood frames supported either from the roof of the building or by the upright members 3.

Resting upon the channel members 5 are the hook ends 8 of downwardly depending 80 straps 9 having right-angled lower ends 10. Secured to the latter by bolts 11 and nuts 12 are sheets of corrugated asbestos 13 upon which is poured gypsum 14. The latter, with the corrugated asbestos, forms an insulating medium which prevents the temperature of the saturated air on the inside 85 of the hood, from being reduced by the cooler air on the outside, to a point which would condense the saturated air, thereby 90 causing drops of water to fall upon the pulp or paper beneath, with injurious results.

As is well known in the art, the hood of a pulp or paper drying machine prevents the saturated air above the dryers from leaving 95 the vicinity of them, for if any of it gets in the room, some of it will be condensed and drop on the wet end of the machine, where it will go directly through the paper and cause it to break in the presses. The hood, therefore, is designed to direct this saturated air to the uptakes 15, 15 by which it is conducted through the roof (not shown) to the outside atmosphere.

Since the saturated air within the hood 105 must be maintained at a temperature at or above the condensation point, in order to prevent drops of moisture falling upon the

- pulp or paper on the dryers beneath, I have provided the combination gypsum and asbestos insulating means before described. These means, because of their low heat conductivity, will prevent the saturated air from being condensed on the inner surface of the ceiling of the hood, which is in contact with the cooler air on the outside. While I employ gypsum in combination with the asbestos for effecting the above result, any other form of heat insulating material such as mineral wool may be used without departing from the spirit of the invention.
- 10 To coöperate with the heat insulating means secured to the top frame of the hood, to prevent the escape of moisture from within the hood, and also to make the latter fire-proof, a corrugated asbestos sheet 16 is suspended from each end of the hood frame, while a corrugated asbestos sheet 17 depends from the top of each side thereof. (See Fig. 1.)
- 15 To lead away any moisture that may be formed within the uptakes 15, 15, which, being constructed of sheet metal, are sufficiently conductive of heat to cause the condensation of the saturated air passing through them, the following means are provided. Attached to the bottom of each uptake 15 is a gutter 18 which is connected at its lowest point to a drain pipe 19 that leads the condensation to a suitable collection point. (See Fig. 3.)
- 20 It will be seen that my hood frame may be easily assembled by bolting the frame members together to receive the asbestos sheets, which are suspended from straps that are hooked over the channel members.
- 25 After the asbestos strips are secured to the frame, the gypsum may be poured upon them as a form to provide the insulating means above described.
- I do not wish to be limited to the details of construction and arrangement herein shown and described, and any changes or modifications may be made therein within the scope of the subjoined claims.
- Having described my invention, I claim:
1. In a drying machine, the combination with a hood therefor, of supporting members in the truss frame of said hood, straps depending from said supporting members, asbestos sheets secured to said straps, and gypsum supported by said asbestos sheets.
  2. In a drying machine, the combination with a hood therefor, of longitudinal truss frame members, transverse members supported between the latter, straps depending from said transverse members, corrugated asbestos sheets bolted to the lower ends of said straps, and gypsum supported by said asbestos sheets.
  3. In a drying machine, the combination with a hood therefor, of uptakes projecting through said hood for conducting vapor-laden air therefrom, and drainage means attached to said uptakes for leading away any condensation therein.
  4. In a drying machine, the combination with a hood therefor, of uptakes projecting through said hood for conducting vapor-laden air therefrom, gutters secured to the bottom portions of said uptakes, and a drain pipe communicating with each gutter for the purpose specified.

In witness whereof I have hereunto set my hand this 14th day of April, 1921.

HAROLD T. BAKER.

Witness:

HOWARD S. SMITH.
